UNITED STATES PATENT OFFICE.

CLAUDE HERBERT ABBOTT, OF LISBON, NORTH DAKOTA.

GAS-PURIFIER.

1,028,419.

Specification of Letters Patent.

Patented June 4, 1912.

Application filed May 15, 1911. Serial No. 627,212.

To all whom it may concern:

Be it known that I, CLAUDE HERBERT ABBOTT, a citizen of the United States, residing at Lisbon, in the county of Ransom and 5 State of North Dakota, have invented certain new and useful Improvements in Gas-Purifiers; and I do declare the following to be a full, clear, and exact description of the invention, such as will enable others 10 skilled in the art to which it appertains to make and use the same.

This invention relates to improvements in gas filters and purifiers especially adapted for use in connection with portable lamps.

15 The principal object of the invention is to provide a simple and efficient device for quickly cooling the gas thus insuring a thorough condensation of the moisture contained in the gas.

20 Another object is to provide a cheaply constructed device of this character which will also remove particles of matter suspended in the gas.

Another object is to provide a device of 25 this character in which the liquid separated from the gas is accumulated in such a way as to be drawn off while the device is in use without interfering with its operation.

A further object is to provide such a device 30 which will occupy a minimum amount of space and may be applied for use upon motor vehicles equipped with acetylene generators or it may be incorporated in other gas lighting systems.

35 Other objects and advantages will be apparent from the following description, and it will be understood that changes in the specific structure shown and described may be made within the scope of the invention 40 as claimed without departing from the spirit of the invention.

In the accompanying drawings Figure 1 represents a side elevation of a gas purifier constructed in accordance with this invention. Fig. 2 represents a central vertical section thereof. Fig. 3 represents a horizontal section taken on the line 3—3 of Fig. 2.

45 In the embodiment illustrated a purifier is shown comprising two inverted cone-shaped casings 1 and 2 arranged one within the other and spaced apart a sufficient distance to provide a small gas chamber 3 between them for a purpose to be described. 50 Both of these casings 1 and 2 are preferably attached to a common support 4 which may

be fastened to the floor of a vehicle on its lower face by any suitable fastening devices or it may be secured to any other part of a vehicle body.

60 A gas inlet pipe 5 discharges into the smaller inner casing 2. The apex of this inner casing 2 has an outlet opening 6 therein through which the condensed moisture passes out into the lower end of the casing 1 from which it may be withdrawn when desired through a drip cock 7. The inner casing 2 is provided in one side wall with a plurality of gas exit openings 8 through which the gas passes to the chamber 3 65 formed between the two casings. In this chamber 3 the gas spreads out into a thin layer and is quickly cooled by contact with the outside casing 1 and any moisture contained in the gas so cooled is condensed and settles in the lower pointed end of the casing 1 from which it may be drawn off through the cock 7 above described. The outer casing 1 is provided with an exit aperture 9 at a point opposite the apertured wall 70 of the inner casing, said aperture 9 being preferably arranged near the support of said casing and through which the gas from the chamber 3 passes to a filter 10 secured to the outer face of said casing 1. This filter 75 80 85 90 95 100 105 110

This filter 10 is preferably provided with removable closures 11 and 12 at its opposite ends and is filled with any suitable filtering material, such as cotton or hair. An outlet pipe 13 is connected with said filter preferably at the end opposite the end which communicates with the aperture 9 of the casing 1. In the use of this device gas is admitted through the pipe 5 to the inner casing 2 and impinges against the imperforate side walls 95 thereof and spreads over said wall and is thereby partially cooled and a portion of the moisture contained therein condensed before the gas passes out through the apertures 8 to the chamber 3. The moisture so condensed passes to the lower end of the casing 2 and out through the opening in the bottom or apex thereof into the casing 1 from which it may be withdrawn through the cock 7. The gas with a portion of its moisture eliminated therefrom passes out through the apertures 8 in the casing 2 into the chamber 3 formed between said casings where it expands into a thin layer which coming in contact with the walls of the outer casing 1 and the inner casing 2 is quickly cooled. This rapid cooling of the

gas causes a thorough condensation of the moisture therein and when the gas passes from said chamber 3 to the filter it is substantially dry. The filter serves to remove 5 any suspended particles of material in the gas and the gas which passes out through the tube 13 is clean and dry ready for consumption in any lamp or burner without the least danger of clogging of the burner.

10 I claim as my invention:—

1. A gas purifier comprising a plurality of casings arranged one within the other and spaced apart, means for supplying gas to the inner casing adjacent the upper portion thereof, said inner casing having gas 15 openings in one side wall, the outer casing having a gas outlet in its side opposite the openings in the inner casing, means for relieving the casings of condensed moisture, 20 and a filter communicating with said outlet,

the latter being located adjacent to the upper portion of the outer casing.

2. A gas purifier comprising a plurality of inverted cone-shaped casings arranged one within the other and spaced apart, means 25 for supplying gas to said inner casing at its larger end, said inner casing having a plurality of gas exit openings in one side wall and a moisture outlet at its apex, the outer casing having a gas outlet in its side 30 opposite the gas exits of the inner casing, and a filter communicating with said outlet.

In testimony whereof I have hereunto set my hand in presence of two subscribing witnesses.

CLAUDE HERBERT ABBOTT.
